[57] CLAIM

The ornamental design for a workspace organizer for attachment to a user interface, as shown and described.

DESCRIPTION

FIG. 1 is a front perspective view of a workspace organizer for attachment to a user interface.

FIG. 2 is a top plan view of the workspace organizer for attachment to a user interface of FIG. 1.

FIG. 3 is a front elevation view of the workspace organizer for attachment to a user interface of FIG. 1.

FIG. 4 is a side elevation view of the workspace organizer for attachment to a user interface of FIG. 1.

FIG. 5 is a back elevation view of the workspace organizer for attachment to a user interface of FIG. 1.

FIG. 6 is a front perspective view of a second embodiment of a workspace organizer for attachment to a user interface.

FIG. 7 is a top plan view of the workspace organizer for attachment to a user interface of FIG. 6.

FIG. 8 is a front elevation view of the workspace organizer for attachment to a user interface of FIG. 6.

FIG. 9 is a side elevation view of the workspace organizer for attachment to a user interface of FIG. 6.

FIG. 10 is a back elevation view of the workspace organizer for attachment to a user interface of FIG. 6.

FIG. 11 is a front perspective view of the workspace organizer for attachment to a user interface of FIG. 1, shown attached to a user interface.

FIG. 12 is a front perspective view of a third embodiment of a workspace organizer for attachment to a user interface.

FIG. 13 is a front elevation view of the workspace organizer for attachment to a user interface of FIG. 12.

FIG. 14 is a front perspective view of a fourth embodiment of a workspace organizer for attachment to a user interface; and,

FIG. 15 is a front elevation view of the workspace organizer for attachment to a user interface of FIG. 14.
